UNITED STATES PATENT OFFICE.

EDMUND D. CHAMBERLAIN, OF WESTFIELD, UNION COUNTY, N. J.

INK-PAD HOLDER.

SPECIFICATION forming part of Letters Patent No. 340,761, dated April 27, 1886.

Application filed March 27, 1885. Serial No. 160,267. (No model.)

To all whom it may concern:

Be it known that I, EDMUND D. CHAMBERLAIN, a citizen of the United States, residing at Westfield township, Union county, State of New Jersey, have invented a new and useful Improvement in Ink-Pad Holders, of which the following is a full, clear, and exact description, reference being had to the accompanying drawings, making part of this specification, 10 in which—

My invention has for its object the construction of an ink-pad holder by which the cloth over the ink will be kept tight and free from wrinkles automatically.

20 In the drawings, A represents the outer casing of the pad-holder; B, the ink-holder; C, a spring located beneath the ink-holder, and D a cloth covering over the ink, secured at all points under and to the bottom plate, 25 E, thus binding the ink-holder, spring, and bottom plate together.

In stretching and securing the cloth D over the ink-holder B the spring C should be depressed, in order that the spring may exert a constant upward pressure upon the holder and 30 gently forcing it all the time against the cloth D, thus automatically keeping the cloth smoothly stretched over the holder B.

I am aware that the cloth covering of ink-pad holders has been held in place and kept 35 stretched by means of an inner retaining-sleeve; but such is not my invention.

Having thus described my invention, what I claim as new, and desire to secure by Letters Patent, is—

40 The ink-holder B and cloth covering D and plate E, in combination with the spring C, placed between the ink-holder and the bottom plate, E, substantially as and for the purpose set forth.

EDMUND D. CHAMBERLAIN.
